CLAIM

The ornamental design for a goggle, as shown and described.

DESCRIPTION

FIG. 1 is an isometric view of a goggle.

FIG. 2 is a front view of the goggle in FIG. 1.

FIG. 3 is a rear view of the goggle in FIG. 1.

FIG. 4 is a right side view of the goggle in FIG. 1.

FIG. 5 is a left side view of the goggle in FIG. 1.

FIG. 6 is a top view of the goggle in FIG. 1.

FIG. 7A is a bottom view of the goggle in FIG. 1; and, FIG. 7B is an enlarged view of a left portion of the bottom view of the goggle shown in FIG. 7A. The corresponding right portion is a mirror image of the view in FIG. 7B.

The even broken lines shown in the figures represent unclaimed portions of the goggle and form no part of the claimed design. The dash-dot lines indicate the boundary of the claimed design and form no part of the claimed design.
